UNITED STATES PATENT OFFICE.

MINOR F. H. GOUVERNEUR, OF BALTIMORE, MARYLAND, ASSIGNOR TO LOCKE INSULATOR CORPORATION, OF BALTIMORE, MARYLAND, A CORPORATION OF MARYLAND.

INSULATOR.

Application filed November 11, 1924. Serial No. 749,145.

The invention relates to suspension or connecting devices for insulators, particularly those of the Hewlett type.

The primary object of the invention, generally stated, is to provide a suspension device for mechanically connecting high tension suspension insulators, together in series or to supports and wire clamps. In the Hewlett type of insulator two arcuate holes are formed in the body in such manner that they interlink within the insulating material with a substantial wall separating them and effectually insulating the metallic connecting devices received by and extending within and through the arcuate holes. Various devices have been provided for effecting connection and in some instances use has been made of U-shaped or J-shaped link or yoke members engaging through the holes or passages in the insulators and connected at their ends by bolts or the like but the well known structures possess many disadvantages, foremost among which is difficulty in assembling.

The object of the invention, more specifically stated, is to provide insulator suspension means including members of curved form adapted to be inserted or threaded through the arcuate holes in the insulators, and connecting means adapted to be engaged upon the ends thereof without the employment of bolts, pins or other securing elements which are difficult to apply, the connecting member having, moreover, auxiliary holding means associated therewith whereby subsequent accidental disconnection or displacement of the parts will be prevented while at the same time disconnection for the purpose of making repairs or replacements may be readily accomplished whenever the occasion arises.

An important object is the provision of suspension means of this character which will possess considerable flexibility so that when a string of connected insulators is suspended the various units may automatically accommodate themselves to the line of tension and be consequently arranged in coaxial relation, the flexibility being, however, limited to such an extent that a string of insulators may be freed from their crate and hoisted into place by connection of a hoist line with an intermediate portion of the

string, without the resultant bowing of the string being sufficient to cause the successive units to come into contact.

A further object of the invention is to provide connection or suspension means of this character in which the various elements are free from sharp corners or projections so that the formation of corona points will be avoided.

Still another object of the invention is to provide connecting or suspension means of this character involving or embodying duplicate parts which are consequently capable of reversal and interchangeability so that there will be no rights or lefts or other complications to cause confusion and delay in assembling.

A further object of the invention is the provision of an improved and simplified construction of such insulator connectors by means of which increased strength, durability and utility may be obtained in addition to the convenience of operation.

To these and other ends the invention comprises the various elements and combinations of elements to be hereinafter more fully described and set forth in the claims hereunto appended.

In the drawings:

Figure 1 is a vertical section through a string of insulators connected by my suspension means, certain parts of the suspension means or devices being shown in section, and other parts in elevation.

Figure 2 is a detail section illustrating the auxiliary holding means more clearly and in greater detail.

Throughout the specification and drawings like parts are designated by like reference characters.

Referring to the drawings in detail, I have illustrated a string of insulators 1 of the Hewlett type and each insulator is formed with interlinking arcuate holes or passages 2 and 3, the former curving downwardly and the latter curving upwardly. These passages interlink within the body of the insulator and are spaced apart or separated by a substantial portion 4 of the insulator.

In carrying out the invention I provide connecting or suspension means including a pair of curved yoke or link members 5 which

are substantially U-shaped or somewhat more than semi-circular with their ends terminating in heads 6 adjacent which are constricted or reduced neck portions 7 defining shoulders 8 at the opposite edges. The yokes or members 5 are of such shape and construction as to be capable of being threaded easily through the passages 2 or 3.

For connecting the ends of the adjacent yoke members I employ a plurality of counterpart connecting members of simple construction. Each of the members 9 is substantially rectangular in form and includes relatively heavy or thick ends 10, side flanges 11, and a web 12 connecting the latter adjacent corresponding side edges thereof. The end portions 10 are preferably of greater depth than the side portions or flanges 11 to give the necessary strength. At its opposite ends, the member 9 is provided with inverted T-shaped slots, the portions 13 of said slots being in the ends 10 and the heads 14 of said slots being spaced by the web 12. The slots or recesses 13 are of a size to receive the constricted neck portions 7 of the yoke members 5, while the heads 6 are each adapted to enter one of the slots 14 between the adjacent end 10 and the web 12. The shoulders 15 formed on ends 10 by the slots 13 are extended inwardly, or toward the center of the members 9 as at 16, so as to overhang the end 6 of the co-acting link which is thus confined between the portions 16 and the rear wall 17 of the slot 13 to prevent relative lateral displacement of the said parts.

To effect suspension of an insulator from one above, a link member 5 is threaded through the passage or hole 2 in the insulator above, a similar link 5 is threaded through the passage 3 in the lower insulator, and the adjacent ends at one side of the yoke are connected by engagement of a member 9 therewith, the connection being effected by moving the member 9 and one end of a yoke 45 together by relative lateral movement so that the head 6 will be received within one of the openings or spaces 14, the neck 7 passing into the slot or recess 13 and engaging against the wall 17 thereof. When the member 9 is then moved longitudinally with respect to the yoke and away from the end thereof, the head 6 will engage behind the extensions 16, the shoulders 8 engaging against the underside or surface 15 of the end portion 10. The corresponding end of the other yoke is engaged with the member 9 in the same manner. The other ends of the yokes are connected by another member 9 in a similar way.

In order to prevent subsequent accidental displacement, use may be made of the auxiliary fastening device 19 which is of a staple or hairpin-like formation and constructed of resilient material such, for instance, as wire of heavy gage or rod of light

gage. The fastening member 19 includes spaced substantially parallel arms 20 and 21 connected by a bight portion 22, the arms being spaced apart a distance practically the same as the width of the web 12 at the central portions of the connectors 9. The arm 20 may be straight throughout its length while the arm 21 may be formed with a lateral end 23 directed toward the arm 20 so as to engage against the outer face of the web 12 of one of the pair of connectors 9.

After the adjacent yokes have been connected as above described, the fastener 19 is engaged over and about the web 12 of one member 9 and is then moved longitudinally while its arms 20 and 21 are sprung apart to permit them to be engaged upon and about the web 12 of the other connector. Upon relieving the outward springing pressure on the arms their natural resilience will cause them to return to their normal or parallel position so that the lateral end 23 will engage against the web and prevent the fastener from accidental withdrawal. The size of the fastener arms, the openings 14 and the heads 6 is such that when the fastener is in place the distance between the arms thereof and the adjacent ends of the heads 6 will be less than the length of the extensions 16 so that the yokes 5 and connectors 9 cannot move relatively a sufficient distance for the heads to clear the extensions 16. It is consequently evident that as long as the fastener 19 is in position it is impossible for the yokes 5 and members 9 to become separated, while in the event of necessity disconnection may be effected in a simple manner by reversing the above described operation subsequent to the spreading apart of the arms 20 and 21 and removal of the fastener.

The thick ends 10 of the connectors 9 connected by the side flanges 11 which are in turn connected by the integral webs 12, will insure great strength so that the suspension device will be easily capable of withstanding the great strain to which it is subjected without there being any danger of spreading of the sides and consequent disengagement of the yokes from the connectors. Another important feature is the fact that the connection of the yokes with the members 9 is such that there is considerable flexibility which will permit automatic accommodation of the insulator units and suspension devices to the line of pull so that each unit will be directly in line with those adjacent and all will be co-axial. Ordinarily, insulator strings are assembled and are taken, usually in crated condition, to the points where their use is needed and the entire string, while still within the crate, is then hoisted into place, the hoisting line or other device being connected with the portion of the topmost connecting device pro-

jecting beyond the end of the crate. After the string is hooked in place the crate is removed. However, with the units connected by the means forming the subject-matter of this invention, the crate may be initially removed and in this instance the hoisting device may be connected with an intermediate portion of the string. While the connecting or suspension devices possess considerable flexibility, as above pointed out, it will be seen that the flexibility is limited so that in case an assembled string is hoisted by engagement of a hoist line or the like with an intermediate portion, the resultant bowing of the string cannot bring the successive insulator units into contact. This feature is important inasmuch as such contact of the units during hoisting would in all probability prove disastrous as the danger of breakage would be considerable.

Connecting and suspension means constructed in accordance with the present invention will be extremely easy to apply on account of the absence of bolts, pins or other similar securing elements which are difficult to handle and insert properly in position, and furthermore, for the reason that the connectors and yokes are all interchangeable and reversible. Initial securing is effected merely by interengagement of the yokes and connectors themselves and permanent securing is accomplished simply by sliding and springing the auxiliary fastener in place. All the parts are of such construction as to possess great strength and durability.

Having now described my invention, what I claim is:

1. Means for connecting insulators having curved insulating passages comprising a pair of similar curved yoke members adapted for insertion through the interlinking passages of successive insulators and terminating in heads adjacent constricted neck portions, and connecting members apertured for the reception of said neck portions and having retaining surfaces co-acting with said heads, said connecting members including intermediate transverse portions spaced from the ends thereof to provide apertures for securing means.

2. Means for connecting insulators having

curved insulating passages comprising a pair of similar curved yoke members adapted for insertion through the interlinking passages of successive insulators and terminating in heads adjacent constricted neck portions, connecting members apertured for the reception of said neck portions and having retaining surfaces coacting with said heads, 55 said connecting members including intermediate transverse portions, in combination with a securing member adapted to extend through the connectors in embracing relation to the intermediate portions thereof 60 and coacting with said heads to prevent disengagement of the connecting members from the yoke members.

3. Means for connecting insulators having curved insulating passages comprising a pair 70 of similar curved yoke members adapted for insertion through the interlinking passages of successive insulators and terminating in heads adjacent constricted neck portions, connecting members apertured for the reception 75 of said neck portions and having retaining surfaces coacting with said heads, said connecting members including intermediate transverse portions, in combination with a securing member adapted to extend 80 through the connectors in embracing relation to the intermediate portions thereof and coacting with said heads to prevent disengagement of the connecting members from the yoke members, said securing member 85 having a lateral portion engaging outwardly of one intermediate portion for preventing withdrawal.

4. Means for connecting insulators having suspension members projecting therefrom 90 and terminating in heads adjacent constricted neck portions, comprising counterpart connecting members apertured for the reception of said neck portions and having retaining seats coacting with said heads, in 95 combination with an auxiliary retaining element extending through both connecting members in engagement with said heads, said members including intermediate web portions, and said auxiliary element embracing said web portions.

In testimony whereof I affix my signature.

MINOR F. H. GOUVERNEUR.
